UNITED STATES PATENT OFFICE.

JOHN HANLON, OF NEW YORK, N. Y., ASSIGNOR TO THE UNITED GAS IMPROVEMENT COMPANY, OF PHILADELPHIA, PENNSYLVANIA.

GAS APPARATUS.

SPECIFICATION forming part of Letters Patent No. 269,929, dated January 2, 1883.

Application filed July 10, 1882. (No model.)

To all whom it may concern:

Be it known that I, JOHN HANLON, of the city and State of New York, have invented a new and useful Improvement in Gas Apparatus, of which the following is a clear, full, and exact description, reference being had to the accompanying drawings, making a part of this specification, in which—

Figure 1 is a front elevation of a carburetor with my improvements attached. Fig. 2 is a longitudinal vertical section of the same. Fig. 3 is a plan view. Fig. 4 is a side elevation. Fig. 5 is a cross-section.

My invention relates to that class of gas apparatus in which steam is decomposed and the resulting gases combined with oil vapor; and it consists in the combination of devices hereinafter explained and claimed.

To enable others skilled in the art to make and use my invention, I will explain the manner in which I have carried it out.

In the drawings, A represents a gas apparatus provided with the independent furnaces B B', each furnace having its own fire-chambers b b' and air-blast for heating the fuel. B is the generating and B' the fixing chamber. The horizontal and perpendicular flue a a' a² leads from the furnace B, at a point above the fuel, c, into stack B'. The flues d d' lead from the superheating-chamber or arched oven D, at a point above the fuel, c', to the exit-pipe D', which conveys the gas to a washer constructed in the ordinary manner. Steam is admitted below the fuel in furnace B through the pipe E, and is superheated by the intense heat in the furnace B. As this heat would be destructive to the carbon, the oil is introduced into the furnace B through the pipes e. Steam being admitted through pipe e², the steam impinges on the oil at e³, which throws the oil in a spray at a point above the fuel, and then mixes with the water-gas of the steam admit-

ted below the fire. The gases thus mixed pass through the flue a a' a² to the furnace B' at a lower point of the heated fuel, and, ascending 45 through the fuel at a lower temperature than the fuel in the furnace B, are fixed without injury to the carbon of the oil. After the gases are thus fixed they pass from the furnace B' through the superheating-chamber D, through 50 the superheating-flues d d' to the exit-pipe, and then through pipe D' to the washer.

Should it become necessary, I turn on the air and steam into furnace B' through the pipe E'. The flue a a' a², while acting as a flue, 55 is a superheater. The chamber D and flues d d' are also superheaters, and by their location in reference to fire-chambers B and B' are an important feature of my invention.

It is evident that by first passing the steam 60 through an intense heat, sufficient to decompose it, and subsequently passing the mixed gases through a lesser heat, but a heat sufficient to fix the gases, I avoid all danger of destroying the carbon of the oil, which is the object of 65 my invention. Should the heat in chamber B' be too intense, I provide a jet of steam through the air-pipe E', which rapidly conducts the gases through the heat, thus preventing any destruction of carbon.

Having thus explained my invention, what I claim as new, and desire to secure by Letters Patent, is—

In a gas apparatus, the furnace B, provided with the steam-pipe E below the fuel, the oil-pipe e and steam-pipe e² above the fuel, and the conducting-flues a a' a², in combination with the furnace B' and the flues D d d', all constructed to operate substantially as and for the purpose set forth.

JOHN HANLON.
